(57) **CLAIM**

The ornamental design for a flat mirror, as shown and described.

DESCRIPTION

FIG. 1 is a front, left perspective view of a flat mirror showing my new design;

FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and

FIG. 9 is an open perspective view thereof; and,

FIG. 10 is another open perspective view thereof.

The broken lines shown on the drawings depict portions of the flat mirror that form no part of the claimed design.
